FURNITURE SPRING CONSTRUCTION

William A. Kalpakoff, Walnut Park, Calif., assignor to Percy Solotoy, Los Angeles, Calif.

Application September 28, 1942, Serial No. 459,899

4 Claims. (Cl. 155—179)

The present invention relates generally to articles of furniture, such as chairs, settees, davenport and the like of over-stuffed type of upholstery, requiring upholstery supports, usually metal springs, and has for its primary object the provision of an arrangement for supporting the yielding back and seat upholstery in a manner which will admit of the use of spring supporting members either of metal or wood, especially wood.

According to the invention, and in keeping with the object just set forth, this application proposes an arrangement in which the spring seat and/or back structure may be accomplished by the use of spring slats alone, doing away with helical and other types of springs dependent wholly upon the use of metal, these spring slats being adaptable to the use of wood as well as metal and being also adaptable to single piece or laminated formation.

With the foregoing general objects and statement, the invention will be better understood and more thoroughly appreciated, from the following description in detail of the best forms thus far devised for carrying the same into practical effect, and by reference to the accompanying drawings, illustrating the same and forming a part of this specification. In the drawings—

Fig. 1 is a perspective view showing the spring seat and back construction herein proposed.

Fig. 2 is a vertical longitudinal sectional view taken therethrough substantially on line 2—2 of Fig. 1.

Fig. 3 is a detail fragmentary view in perspective of certain parts cooperating to form sockets movably receiving the lower ends of the slats of the spring back support.

Fig. 4 is a detail fragmentary front view of one end portion of the front upholstery rail.

Fig. 5 is a vertical longitudinal sectional view through the seat frame showing a slightly modified arrangement of spring slats.

Fig. 6 is a perspective view of a portion of the front upholstery rail showing a laminated spring slat.

Fig. 7 is a view similar to Fig. 2, illustrating a modified arrangement particularly as to the spring back structure.

Fig. 8 is a horizontal sectional view through the upper portion of the spring back arrangement, taken substantially on line 8—8 of Fig. 7.

Fig. 9 is a detail perspective view of the upper upholstery rail, and portions of the spring slats, of the arrangement shown in Figs. 7 and 8.

Fig. 10 is also a view similar to Fig. 2, but illustrating a further modified arrangement in both the back and seat elements, taken on the line 10—10 of Fig. 11.

Fig. 11 is a plan view, partly in section, taken on the line 11—11 of Fig. 10.

Fig. 12 is a broken, perspective view of a portion of the back spring element.

Fig. 13 is a vertical, broken section showing a still further modified back element.

Figs. 14 and 15 are sections of modified details hereinafter more fully described.

Referring now to the above described figures of the drawings, there is shown in Figs. 1 and 2, a seat frame consisting of side rails 10 and a front rail 11, in connection with the lower portion of a back frame, side rails 10 being suitably connected to the lower ends of, and at a suitable angle to, the upright side rails 12 of the back frame, which also includes spaced apart lower inner and outer cross rails 13 and 14 and a single upper cross rail 15.

Considering first the spring seat arrangement of the seat frame, there is preferably an intermediate longitudinal rail 16 centrally between, and parallel to, the side rails 10, which intermediate rail 16 is connected at its forward end to the front rail 11 and may be similarly connected at its rear end to the lower inner cross rail 13 of the back.

Above and substantially parallel to the front rail 11 is an upholstery rail 17, preferably made up of an upper bar 18 and a lower bar 19, the latter of which is notched at a central point and at its ends, as at 20, to receive the upper forward ends of spring rail supporting slats 21. These slats are fixed to the rail 17 as by means of screws and like fastenings 22 driven upwardly into the lower bar 19 as plainly seen in Fig. 4.

The rail 17 is supported in a floating position to yield vertically toward and away from the front frame cross rail 11, by reason of the above supporting slats 21 whose lower rear ends are anchored to supporting blocks 23 securely fastened on the intermediate seat frame rail 16 and laterally against the inner faces of the seat side rails 10, at points intermediate the ends of said rails 10 and 16, so that the slats 21 rise forwardly and upwardly at substantial angles.

It will be noted from Fig. 2, that the rear anchored ends of spring slats 21 are below the upper surface of the seat frame while the forward ends thereof, yielding supporting the floating rail 17 are substantially above the seat frame.

The upper bar 18 of the front seat rail 17 is

notched to receive the forward ends of a series of spring seat slats 24 whose rear ends extend loosely through the notches of a bar 25 securely anchored to, and along, the lower inner cross rail 13 of the back, as plainly seen by a comparison of Figs. 1 and 2. These slats 24 which form the seating surface of the seat frame, are normally slightly curved and free to shift lengthwise through the slats of the confining bar as the seating surface yields downwardly under load and the floating front seat bar 17 is shifted downwardly against the tension of its supporting slats 21.

Preferably the seat slats 24 are of laminated wood construction. They may be of two-ply as in Figs. 1 and 2, or three-ply as seen at 24a in Fig. 6, and the layers thereof may be solidly joined from end to end, or so joined only at their rear ends as at 24b in Fig. 5 where their forward portions are shown vertically spaced with the upper layers secured in the notches of bar 18 and the lower layers secured, along with the forward ends of the supporting slats 17, in the notches of bar 19.

The spring surface of the back frame, for the yielding support of the back upholstery, may consist of a series of curved spring slats 26 whose upper ends are securely anchored at 27 in pockets formed in the upper back rail 15 and whose lower ends are vertically adjustably disposed in pockets formed by the notches of a bar 28 secured against an intermediate cross rail 29 of the back frame and in a supplemental pocketed rail 30 secured to rail 29. This construction is plainly shown in Figs. 1, 2 and 3 and is well adapted, like the described spring seat arrangement, to the use of either solid one-piece, or laminated, wood spring slats.

As shown in Figs. 7, 8 and 9, the spring back structure may conform more closely to the spring seat arrangement by having the upper ends of the curved back spring slats 26a fixed at their upper end to an upper floating back rail 31 spaced forwardly of the upper stationary back rail 15a. This floating rail 31 will be spring supported by relatively short supporting spring slats 32 of laminated or solid construction, like the supporting spring slats 21 of the floating front seat rail 17. For this purpose the spring slats 32 will be secured at their upper ends to the floating back rail 31 and similarly secured at their lower ends to a supplemental intermediate cross rail 33 of the back frame.

It will be understood that in this modified construction of back spring arrangement, the lower ends of the spring slats 26a will be vertically slidably adjustable in the same manner, and by the same means, as described in connection with the structural form of Figs. 1, 2 and 3, and it is obvious that in either instance the spring back and seat arrangement, as thus fully described in alternate forms, makes it possible to substitute wood spring members for metal and in fact eliminates all necessity for the use of metal except for the anchorage and connection of the parts.

In the formation of the resilient slats of laminated construction, it is contemplated the laminae may be bent with glue between them and held in such form until the glue dries and hardens so that the bent form will thus be retained, and thus provide for greater strength than a single steamed and bent piece.

The modified construction shown in Figs. 10 to 12 comprises a rear corner-post 50 of a frame 51. Supporting blocks 52 are fastened within the frame 51 at opposite sides thereof. Suc-

cessively longer leaves 53, 54 and 55 of seat springs are screwed upon the supporting blocks 52. The longest leaves 55 support cross bars 56 and 57 which are fastened cross-wise upon the ends of such leaves at opposite sides of the points of support for the leaves.

A center rail 58 supports a similar series of leaves 53, 54 and 55. Screws 59 fasten the center leaves upon the center rail 58.

Series of bowed slats 60 have their forward ends fastened in place upon the cross bar 57, by an upper bar 61, which is notched to receive the forward ends of the slats 60 in the manner of the upper bar 18. Screws 62 fasten the upper bar 61 and the forward ends of slats 60 to the cross bar 57. The rear ends of the slats 60 are slidable between the cross bar 56 and an upper bar 63 as in the case of the bar 25. It is to be understood that the lower face of the upper bar 63 is notched similarly to the bar 25. The upper bar 63 is secured to the cross bar 56 by means of screws 64, permitting longitudinal movement of the rear ends of the slats 60, as suggested at 65 in Fig. 10.

The back member comprises a cross rail 66 which supports a plurality of vertically disposed, superposed leaves 67 and 68 at opposite sides of the back, by having such leaves screwed at their mid-portions to said cross rail. A cross bar 69 is fixed to the upper portions of the longer leaves 68 while a slotted cross bar 70 is fastened to the lower ends of the leaves 68. Slots 71 in the lower cross bar 70 receive the lower ends of bowed back slats 72, which have their upper ends fastened to the cross bar 69. The slots 71 are arranged to receive the lower ends of the slats 72 as said slats are flattened by a person leaning against the back of the chair, davenport or love seat embodying the present invention.

The modified construction shown in Fig. 13 comprises a frame 73 having a rear corner-post 74 and a fixed cross rail 75. A series of slats 76 have their lower ends fastened to the cross rail 75 and have their upper ends free, except that a cleat 77 is screwed to the upper, free ends of the slats 76.

Fig. 14 shows a rail 78 which is an alternative construction for rail 15, to which slats 26 are fastened. Fig. 15 shows a bar 79 that is an alternative construction for joining the slats 24 to a floating front rail.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. An article of furniture including a supporting seat frame having rigid front and rear cross rails and a series of rigid longitudinal rails, a series of short flat resilient slats anchored at their rear ends in connection with said longitudinal rails intermediate the ends of the latter, a floating rail above and parallel to the front cross rail and to which the forward ends of said resilient slats are secured to resiliently support the floating rail, a series of spaced parallel seat slats of flat resilient nature secured at their forward ends to said floating rail and extending longitudinally of the seat frame above the same and

said first named slats and rearwardly beyond the rear cross rail, and a notched member secured along the rear cross rail and forming therewith a series of openings in which the rear ends of said seat slats are longitudinally slidably confined and supported.

2. An article of furniture including a supporting seat frame having a front cross rail and a series of longitudinal rails, supporting blocks secured to said longitudinal rails intermediate the ends of the latter, flat resilient slats anchored at their rear ends in connection with said seat blocks and projecting at their forward ends above the front rail, a floating rail above and parallel to the front cross rail and to which the forward ends of said resilient slats are secured to resiliently support the floating rail, a series of spaced parallel seat slats of flat resilient nature secured at their forward ends to said floating rail and extending longitudinally of the seat frame above the same and said first named slats, said frame having at its rear portion a cross rail, and a notched bar secured to said rear rail, the notches forming pockets through which the rear ends of the seat slats are supported in lengthwise slidable relation.

3. In a resilient seat structure, a seat supporting frame having at its forward portion a cross rail, upper and lower series of flat resilient seat slats longitudinally above the frame in laterally spaced relation to form an upper spring seating

5 surface, a floating rail above and parallel with the said forward frame rail and to which the forward ends of said seat slats are fixed, the upper and lower series of slats being respectively secured to the upper and lower surfaces of said floating rail, means at the rear of the frame forming openings receiving the rear ends of said slats in superposed relation and in lengthwise movable and laterally confined relation, and a lower series of forwardly and upwardly inclined relatively short flat resilient supporting slats fixed at their upper forward ends to the floating rail and at their lower rear ends within the seat frame intermediate the forward and rear ends of the frame.

4. In an article of furniture, a spring element comprising a supporting member, flat, resilient slat means extending from the supporting member, a floating rail spaced from the supporting member and floatingly supported by the slat means, a series of bowed, laterally spaced, flat, resilient slats fastened to said floating rail, a second series of laterally spaced, flat, resilient slats fastened to said floating rail, one series being superposed with respect to the other series and portions of the floating rail separating adjacent ends of superposed slats to cause one series to resist flexing of the other series, and means to receive opposed portions of the slats in longitudinal shiftable movements of the slats.

30 WILLIAM A. KALPAKOFF.
